COLLAPSIBLE ROOF CRANE

Elmer Fredrick Maxeiner, St. Louis, Mo.

Application March 10, 1948, Serial No. 14,083

2 Claims. (Cl. 248—237)

1

This invention relates generally to portable cranes, and more particularly to such cranes that are used by roofers and other workmen to hoist supplies and materials to a higher level from some point therebelow, and has as its principal object to so construct such a crane that it will be extremely simple and of a minimum number of members.

Another important object is to provide such a crane that it will be relatively light in weight and yet sturdy enough to withstand the loads to which it may ordinarily be subjected.

A further object of the invention is to provide a collapsible or knock-down portable crane, which will be self-supporting or retaining in operative position, so that no bolts, screws nor similar fastening elements need be used to anchor the mechanism in place.

An added object of my invention is to so construct such a device that it may be formed of pipe lengths to consist of but two units or members, so that these members may be interlocked together to be set up into operative position, and may be quickly and easily separated into the two units for removal from the job when no longer needed.

Another added object of the invention is to so construct the jib member of the mechanism so that any of the various materials used on the job, such as roofing paper, bags of cement, or any other relatively heavy work materials may be deposited on the lowermost end of the jib member to add sufficient weight to anchor the jib member to the supporting wall or roof.

Still another object of the invention is to so construct the mechanism of the kind described, that it will press downwardly against the roof at a pair of spaced intervals to anchor the mechanism thereat, the bearings at said anchorage intervals being arcuate or rounded so as not to cause any damage to the roof and to be self-adjustable to accommodate any positions which may be necessary for placing the mechanism into operative position.

Still further objects of the invention reside in the construction of a device of the kind described, which will be simple and economical in construction cost, light in weight when compared to the load to be carried, strong and sturdy, neat and attractive in appearance, adjustable so as to be

useful in various types of work and in various installations, and which will be otherwise satisfactory and efficient for use wherever deemed applicable.

5 Many other objects and advantages of the construction herein shown and described, and the uses thereof, will be obvious to those skilled in the art to which this invention appertains, as will be more clearly apparent from the disclosures herein given.

To this end, my invention consists in the novel arrangement, construction and combination of parts herein shown and described, as will be more clearly pointed out in the following specification.

10 In the drawings, wherein like reference characters represent like or corresponding parts throughout the views,

Figure 1 is a perspective view showing the device as set up in operative position, showing the loading articles in dotted lines;

Figure 2 is a diagrammatic side elevation showing the cooperation of the parts of the device;

15 Figure 3 is a fragmentary detail showing the adjustable positioning of the upright member upper end to the inclined jib member;

Figure 4 is a fragmentary detail showing the detachable interlocking of the upper end of the tie rod with the jib member; and

20 Figure 5 is a fragmentary side view, showing the lower, trough end of the jib member, and loaded slightly differently (in dotted lines) than in Fig. 1.

25 Referring more particularly to the drawings, wherein I have illustrated a preferred embodiment of my invention, 1 indicates any suitable type of substantially horizontal supporting wall, such as a floor or a roof of a building structure, and to which or from which any kind of materials are to be carried.

30 It is very desirable that the crane be used for this manner of transportation between different levels, be of light weight so that it can be most readily handled from job to job, and that it be of few members so as to avoid loss or misplacement of its parts, and in this particular instance I have been able to reduce the device to but two units or members, the same being indicated as the jib member 2 and the upright or vertical supporting member 3 for detachable connection thereto.

35

40

45

50

The jib member 2 is preferably formed of an elongated length of hollow pipe of suitable diameter and strength so as to be able to withstand the loads to which the device may be subjected, without any bending or deformation of the same. The forward end of the pipe may have an eye bolt 4 extending thereto and preferably welded in place so as to prevent any relative movement between the two, or any possible loss of the eye element, and the ropes, sheaves or other means may be carried by said eye element to support the load L suspended from the same.

The rear end of said jib pipe has a cross pipe 5 welded or otherwise rigidly secured thereto and to provide a rounded bearing against the roof, this rounded bearing preventing the deep cutting or other damage to the roof itself thereat. A scoop, trough or other shape of frame 6 is fixed to and carried by the rear or lowermost end of the jib pipe, as by bending a length of pipe so that it extends rearwardly and forwardly of the cross pipe 5, and also extends cross-wise or transversely of the jib pipe, somewhat as shown, and into this scoop or trough frame there may be deposited practically any sort of material at hand, for providing sufficient weight to anchor this end of the jib pipe against the roof thereat. For example Fig. 1 illustrates the use of several rolls of roofing felt or paper and upon which a bag of sand, gravel or cement may be superimposed, while Figure 5 shows the use of fewer rolls of paper in addition to the bag of material in place.

Two sets of adjustment openings 7 and 8 respectively, are positioned at separated intervals along the length of the jib pipe, the openings 7 being in a plate 9 welded or otherwise rigidly secured to the jib pipe near the forward end of said pipe, while the series of openings 8 are spaced apart in the plate 10 similarly secured to said jib pipe between the plate 9 and the rear end of said jib pipe.

The upright member 3 is formed of the upright pipe element 11 welded or otherwise secured at its lower end to a cross-pipe 12 so that the member 3 is in the form of an inverted T, the member adapted to be supported on the roof by said rounded shape of the pipe 12 of the T and provide a rounded bearing with the roof in somewhat the same manner and for the same reasons as that given in connection with the cross pipe 5.

A pair of diagonally extending struts interconnect or tie-in the upright pipe 11 with the cross pipe 12, as by welding at the ends of said struts 13-13.

The upper end of said upright pipe 11 is preferably provided with a pair of ears 14-14 spaced apart a distance to receive the plate 9 therebetween, and is provided with a pin or bolt 15 transversely secured permanently in place as indicated, so that said pin 15 is adjustably received within the series of slots 7 of the plate and bears against the upper, closed end of said slots thereat to take up the load between the jib member and upright member.

A tie-rod 16 is pivotally secured at its lower end to the lower end of the upright element of the upright member, the other end of said tie-rod being in the form of a snap-fastener having a movably held pin 17 resiliently held in place thereat. An eye element 18 is fixed to the upright pipe 11 at a height to detachably receive and interlock with the fastener pin 17 so as to hold the tie-rod in inoperative position collapsed against and substantially parallel with the said

upright pipe 11 when the crane is in knock-down form.

When the device is being set up into operative position, as illustrated in Figs. 1 and 2, the tie-rod is swung about its lower end until the snap fastener pin can be detachably inserted through the proper opening 8 in the plate 10. The dotted line in Fig. 2 indicates the arc of swing of the tie-rod 16.

The adjustments shown permit of shifting the jib member forwardly or rearwardly of the end of the roof being in position to hoist materials, and to change the angularity of inclination of the jib.

Thus it is seen that I have provided a hoisting mechanism consisting of a crane made of but two cooperating members, adjustably and detachably interlocking with one another so that the same can be set up into operative position in the shortest possible time, and which can be dismantled or knocked down into collapsed inoperative position just as readily, and which permits use of the materials closest at hand on the job, for providing the weight W to anchor the rear end of the jib member in place without the use of bolts, screws, boards, or other extraneous fastening means which will mar and damage the roof, and when set up will lift the load L efficiently and satisfactorily.

Having thus described my invention, it is obvious that various immaterial modifications may be made in the same without departing from the spirit of my invention; hence I do not wish to be understood as limiting myself to the exact form, construction, arrangement or combination of parts herein shown and described, or the uses mentioned, except as limited by the state of the inventive art and the claims hereunto appended.

What I claim as new and desire to secure by Letters Patent is:

1. In a portable knock-down roof crane consisting of two members, one of said members comprising an upright pipe, a substantially circular cross-sectioned transverse pipe fixed to the lower end of said upright pipe to provide a pivotal bearing engageable thereat with the roof, a tie rod pivotally secured at one end to said lower end of said upright pipe, means on said pipe to detachably latch the upper end of said tie rod thereagainst into collapsed inoperative position closely adjacent said pipe, said second member comprising an inclined pipe to provide a jib, means on said inclined pipe to adjustably interlock with the upper ends of said upright pipe and with said tie rod, a substantially circular cross-sectioned transverse pipe fixed to the lower end of said jib pipe to provide a rounded bearing thereat with said roof, and a frame on said lower end of said jib pipe and extending transversely as well as forwardly and rearwardly of the same to provide a trough to receive roofing materials removably deposited thereon and to anchor the crane to the roof thereat.

2. In a portable crane adapted to be self-supported in operative position on a substantially horizontal supporting surface and consisting of an elongated jib pipe, an upright pipe detachably connected at its upper end to said jib pipe, means permanently secured to the rear end of said jib pipe and extending forwardly and rearwardly thereat to form a platform to removably receive articles of roofing material thereon in sufficient weight to anchor said jib pipe thereat, a tie rod movably carried at its lower end by the lower end of said upright pipe to be swung

out at an angle to said upright pipe or be superimposed relatively closely thereagainst to be substantially co-extensive therewith, locking means carried at the upper end of said tie rod, and co-operating locking means intermediate the ends of said jib pipe and on said upright pipe, whereby said first-mentioned locking means may be moved to detachably interlock with either of said cooperating locking means to hold said tie rod either co-extensive with said upright pipe or at 10 an angle thereto.

ELMER FREDRICK MAXEINER.
